GAS CONTROL SYSTEM

Hubert T. Sparrow, Edina, Minn., assignor to Honeywell
Inc., a corporation of Delaware
Filed May 9, 1961, Ser. No. 108,804
6 Claims. (Cl. 158—115)

The present invention is directed to a gas burner control system for the efficient utilization of a plurality of pilot gas flow rates, more specifically the present invention is directed to the use of a fluid amplifier for switching gas between two burners for efficient burning of the gas under widely varying flow rate conditions.

There is a class of gas control valves that are pilot operated and utilize a gas flow through the pilot operator for operation of the main valve member itself. Due to the construction of certain of these valves, the gas used to operate the main valve is vented or emptied into the pilot gas line. This creates a varying flow of gas in the pilot gas line and creates a problem in the design and operation of the pilot burner. As a general rule, the pilot burners must be designed for a specific gas flow rate in order to burn the pilot gas efficiently. When the pilot gas flow rate varies due to the venting of the control gas of the valve into the pilot line, it is sometimes impossible to design a single pilot burner that will efficiently burn all of the varying volumes of available pilot gas. With this situation it is necessary to provide some way of varying the means for burning the pilot gas so that efficient operation can be obtained.

The present invention is directed to the use of a fluid amplifier in the pilot gas outlet line between the pilot gas outlet and the pilot burner. The fluid amplifier is a flow control device having no moving parts that is capable of switching a gas flow between two different outlets. In the present case, the fluid amplifier supplies gas at a low rate to the main pilot burner. Upon an increase of pilot gas being available due to the control gas being vented into the pilot line, the fluid amplifier switches and supplies part of the gas in the pilot line to the pilot burner and part of the gas to a second small burner. This division of the gas allows for efficient and clean utilization of all of the gas flow in the pilot outlet line and is accomplished without involving any moving parts in the device. As such the device is fool-proof and has long trouble-free operation. The fluid amplifier also can be built for a very nominal price and allows for straight-forward design of the pilot burners thereby eliminating the cost of complicated arrangements at the pilot burners themselves for the utilization of varying flow rates of gas.

It is the primary object, therefore, of the present invention to disclose a gas burner control system for the utilization of a plurality of gas flow rates wherein a fluid amplifier switches the gas between the main or first burner and a second burner so that the gas can be efficiently utilized.

It is a further object of the present invention to disclose a control system specifically adaptable for use with a manifold type of gas valve that has a varying internal control gas flow that is vented into the pilot gas line, and where this pilot gas is switched between two burners by a fluid amplifier having no moving parts.

Another object of the present invention is to disclose a highly simplified and very inexpensive means of disposing of varying flow rates to a pilot burner when the pilot burner is continuously operated as a means of igniting a main burner.

These and other objects will become apparent when the present drawing is considered along with its associated specification.

2

FIGURE 1 is a schematic representation of a manifold type gas valve of the pilot operated type which utilizes a fluid amplifier for switching between two burners thereby disposing of varying flow rates efficiently;

5 FIGURE 2 is a cross-section of one particular fluid amplifier showing a low gas flow rate, and;

FIGURE 3 is a cross-section of the same fluid amplifier as FIGURE 2 but showing the flow path at a high gas flow rate.

10 In FIGURE 1 there is schematically represented a complete gas burner control system that utilizes a manifold type of gas valve generally disclosed at 10. The valve 10 has been blocked in by dotted lines and incorporates the normal functions of a manifold valve that are usually found in a single valve body or construction. For clarity's sake the individual functions have been in turn broken down and shown in conventional schematic form. The valve 10 has a gas inlet pipe 11 that is connected to a pilot safety valve 12 of conventional construction. The valve 12 supplies a pilot gas line 13 with a continuous supply of gas through a restriction 14 so that the gas flowing in the pilot gas line 13 is nearly atmospheric in pressure. The pilot gas line 13 has an outlet at 15 from the manifold gas valve 10. Incorporated in the safety pilot valve 12 is a thermocouple operated safety pilot having thermocouple conductors 16 that extend to a thermocouple 17 of conventional construction. The main gas outlet of valve 12 is supplied to a pipe 20, that is in turn supplied to a main gas valve 21. The main gas valve 21 has inlet 22 and an outlet 23 with a valve 24 between the inlet and the outlet for control of the main gas flow. The valve 24 operates against valve seat 25 and is moved by a stem 26 that is mounted on a diaphragm 27. The diaphragm 25 is supported by a spring 30 from a web 29. The valve structure described is a conventional diaphragm operated valve structure and its operation will be outlined in the present specification.

40 A control gas line 31 is connected to the valve 21 and has a continuous supply of gas to a thermostatically controlled valve 32. The thermostatically controlled valve 32 has a bellows 33 and a bulb 34 and tube 35 that are filled with a temperature expansive fluid. The bulb 34 senses a temperature to be controlled and supplies a varying pressure to a bellows 33 to open or close the valve 32 to allow gas into a pipe 36 to an upper chamber 37 of the valve 21. The gas supplied to the chamber 37 by the pipe 31, valve 32, and pipe 36 supplies a bias to the upper side of the bellows 27 to force the valve 24 open from its valve seat 25. This occurs whenever the valve 32 is opened.

45 The gas supplied to chamber 37 is vented by pipe 40 through an orifice 41 so that near an atmospheric pressure occurs in the outlet portion 42 of the vent pipe. 50 The vent pipe is connected at 43 to the pilot gas line 13 and exists from the manifold valve 10 at the pilot gas outlet 15. The valve 21 has a main gas outlet pipe 44 that exists at 45 from the manifold valve 10 to the gas burner 46 of any convenient design. The pilot gas outlet 15 is connected to a fluid amplifier 50 which supplies pilot gas to a pilot burner 51 and a second burner 52. The details of the fluid amplifier 50 will be explained below but it is enough at this point to note that the fluid amplifier 50 continuously supplies a gas from the outlet 15 to the burner 51 to maintain a continuous safety pilot for igniting burner 46 and heating thermocouple 17.

55 In order to better understand the function of the fluid amplifier 50, a description of operation of the unit disclosed in FIGURE 1 is believed necessary. Gas is supplied to pipe 11 and continuously is fed to the pilot outlet 15 by the valve 12. At all times when pilot gas is

available at outlet 15 it flows through the fluid amplifier 50 to the pilot burner 51. When the pilot burner 51 has been ignited and is burning it heats thermocouple 17 which in turn supplies voltage to the conductor 16 to operate the safety pilot valve 12. The safety pilot valve 12 supplies gas to pipe 20 and in turn to the valve 21. The valve 21, shown in an open position allows gas flow to the pipe 44 and in turn to burner 46 which is ignited by the pilot 51. The gas flowing in pipe 20 is also supplied to the pipe 31 to the control valve 32 and to the upper side of the diaphragm 27. This control gas flows through the pipe 40 and out of the outlet 15 to the fluid amplifier 50. This gas flow is split in the fluid amplifier 50 and flows both to the pilot 51 and to the secondary burner 52 where it is burned off in an efficient manner.

If the bulb 34 senses a temperature which has been satisfied by the heating effect of burning gas on the burner 46, the bulb causes the fluid fill contained therein to expand and compress the bellows 33. The expansion of bellows 33 closes valve 32 thereby cutting off the flow of gas to the chamber 37. The reduction in flow of gas to chamber 37 reduces the pressure on the top of the bellows 27, and the spring 30 and the gas pressure on the under side of the diaphragm 27 forces the diaphragm in an upward direction closing the valve 24 against the valve seat 25. This removes the gas from the burner 46 and also prevents gas flow from the chamber 37 to the pipe 40 and to the outlet 15 of the pilot line. As such the gas available at the outlet 15 of the pilot gas line is reduced. This reduction in gas is sensed by the fluid amplifier and the entire gas flow is then switched by the fluid amplifier 50 to the burner 51 where a continuous safety burner remains lit. At any time that the main valve 21 is opened through the opening of the temperature control valve 32, an increase in gas flow in the outlet 15 is sensed by the fluid amplifier and is appropriately split between the burners 51 and 52.

To the present point a description of operation of the fluid amplifier 50 has not been specifically described. The fluid amplifier 50 can be any one of a number of types of fluid amplifiers that are becoming quite commonly known. The fluid amplifier 50 could be of a type disclosed in a patent issued to Mr. Billy M. Horton on March 13, 1962, with number 3,024,805, or could be of the type disclosed in the Richard J. Reilly application filed November 16, 1960, and assigned the Serial No. 69,645, now Patent No. 3,030,979, issued April 24, 1962. These two patents disclose various types of fluid amplifiers that can be used with the present device and the selection of the fluid amplifier is a matter of individual choice. In order to completely disclose a fluid amplifier system one particular type of fluid amplifier is shown in FIGURES 2 and 3. In FIGURES 2 the amplifier is shown in the low flow position wherein gas is supplied to burner 51 alone. In FIGURE 3 the amplifier 50 is shown in its higher flow condition wherein the gas is split and is supplied to both the burners 51 and 52.

The fluid amplifier 50 is made of a block of metal 53 that has a hole 54 drilled straight through the block. The hole 54 has a pipe 55 inserted in the hole. The pipe is notched at 56 and is completely open at 57. The end of the hole 54 is plugged at 60. A second hole 61 is drilled adjacent to the hole 54 and intersects two holes 62 and 63 that are drilled into the top of the block 53 and which intersect the holes 61 and 54. A plug 64 blocks the end of the hole 61 in a fluid tight manner.

A threaded opening 65 is provided with a screw 66 that varies the gas flow through an orifice 67 that is drilled in the wall 70 that separates the holes 54 and 61. The hole 67 is drilled through the threaded opening 65 prior to the insertion of the screw 66. To complete the fluid amplifier 50, the burners 51 and 52 are connected to the holes 62 and 63.

It will be noted that the fluid amplifier 50 disclosed in FIGURES 2 and 3 is identical except for the gas flow

outlined in the unit. In FIGURE 2 a relatively low gas flow rate is indicated. The gas flows into pipe 55, which is connected to the outlet 15 of the manifold valve 10. The gas flow in pipe 55 flows through the notch 56 and through the hole 67. This gas flow, being relatively small in volume tends to move upward into pipe 62 where it attaches to the wall of the pipe by an action as described in the above referenced pending applications. The gas flow through the orifice 67 is quite slight and follows through the hole 61 and joins in the pipe 62 to flow to the pilot burner 51. This is the operation of the unit as it exists at relatively low gas flow rates.

In FIGURE 3 an increased gas flow rate to pipe 55 is shown. The flow rate still allows gas to flow through the notch 56 and upwardly into the manifold area above the notch 56. The increased gas flow rate causes an increased gas flow in the hole 67 and forms a jet at 72 that impinges on the side of the gas flow from the notch 56. This jet forces the gas flowing up through the notch 56 to move away from the wall 73 of the hole 62 and over to the splitter 74 which is formed between the holes 62 and 63. The gas flowing up through the notch 56 splits around the splitter 74 with some of the gas passing up to the burner 51 while the remainder of the gas passes up to the burner 52. The unit is designed so that the gas flow up through 51 remains the same or close to the same regardless of whether it is the condition shown in FIGURE 2 or in the condition shown in FIGURE 3. The hole 63 to the burner 52 drains off any excess gas and burns it efficiently at burner 52.

It will be noted that the fluid amplifier 50 disclosed in detail in FIGURES 2 and 3 has no moving parts whatsoever. The amplifier switches from the pilot burner 51 to the second burner 52 merely based on the gas flow rate entering pipe 55 which in turn is connected to the pilot outlet 15. It is thus obvious that a unit has been provided that can conveniently switch from one burner to two burners whenever the gas flow rate increases so that the gas flow can be economically and efficiently utilized in the burner. It is further noted that the pilot 51 is continuously supplied with a gas flow so that a continuous safety pilot is available for igniting the burner 46 and for heating the thermocouple 17. Upon a decrease in gas in pipe 55, the fluid amplifier 50 switches back to the condition shown in FIGURE 2.

The resulting feature of requiring but one pipe (from 15 to 55) to supply both the normal pilot gas flow and also to bleed off the gas from the top diaphragm chamber 37 has certain and important economic and increased safety advantages. The user only has to install one pipe from the valve to the fluid amplifier pilot burner combination. If that one pipe should become plugged or crimped shut by bending, the pilot light will go out causing safety shutdown of valve 12, and since the pressure could then not be bled out of chamber 37, the valve 21 could not open even if valve 12 should remain open for some unnatural reason.

The present invention, as specifically disclosed in FIGURES 1 through 3, is only a typical application of the principle of applying the fluid amplifier to the varying gas flow rates in a gas burner control system. Since many possible combinations of valve devices and fluid amplifiers could be used, the applicant wishes to be limited in the scope of the present invention by the appended claims.

I claim as my invention:

1. A gas burner control system for the utilization of a plurality of gas flow rates including: gas control means supplied with a combustible gas and having gas outlet means; said gas outlet means normally supplied with at least one gas flow rate; fluid amplifier switching means wherein a first gas flow is directed at a side of a second gas flow with said flows connected to said gas outlet means and said amplifier means having two outlets with each outlet connected to a separate burner; a first said

burner being normally supplied with gas through said amplifier means to maintain a flame; and a second said burner adjacent to said first burner and ignited by said flame; said control means increasing the gas flow to said gas outlet means upon operation of said gas control means; said increased gas flow switching said fluid amplifier means to divide said gas flow between said two burners for efficient utilization of said gas.

2. A gas burner control system for the utilization of two gas flow rates including: gas control means supplied with a combustible gas and having gas outlet means; said gas outlet means normally supplied with at least one gas flow rate; a switching type fluid amplifier wherein a first gas flow is directed at a side of a second gas flow with said flows connected to said gas outlet means and said amplifier having two outlets with each outlet connected to a separate burner; a first said burner being a pilot burner being normally supplied with gas through said amplifier to maintain a pilot flame; and a second burner adjacent to said pilot and ignited by said pilot flame; said control means increasing the gas flow to said gas outlet means upon operation of said gas control means; said increased gas flow switching said fluid amplifier to divide said gas flow between said pilot burner and said second burner for efficient utilization of said gas.

3. A gas burner control system for the utilization of a plurality of pilot gas flow rates including: gas control means supplied with a combustible gas and having a main gas outlet and a pilot gas outlet; said pilot gas outlet normally supplied with at least one gas flow rate; a switching type fluid amplifier wherein a first gas flow is directed at a side of a second gas flow with said flows connected to said pilot gas outlet and said amplifier having two outlets with each outlet connected to a separate pilot burner; one said pilot burner being normally supplied with gas through said amplifier to maintain a pilot flame; and a main burner connected to said main gas outlet adjacent to said pilots and ignited by said pilot flame whenever said main gas outlet is supplied with gas by said control means; said control means increasing the gas flow to said pilot gas outlet whenever said main burner is supplied with gas; said increased pilot gas flow switching said fluid amplifier to divide said pilot gas flow between said two pilot burners for efficient utilization of said pilot gas.

4. A gas burner control system for the utilization of a plurality of pilot gas flow rates including: a manifold gas valve supplied with a combustible gas and having a main gas outlet and a pilot gas outlet; some of said gas being used for control of said manifold valve and connected to said pilot gas outlet; said pilot gas outlet normally supplied with at least one gas flow rate; fluid amplifier divider means having no moving parts wherein a first gas flow is directed at a side of a second gas flow with said flows connected to said pilot gas outlet and said amplifier means having two outlets with each outlet connected to a separate burner; one said burner being a pilot burner and normally supplied with gas through said amplifier means to maintain a pilot flame; and a main burner connected to said main gas outlet adjacent to said pilot burner and ignited by said pilot flame whenever said main gas outlet is supplied with gas by said manifold valve; said manifold valve increasing the gas flow to said pilot gas outlet whenever said main burner is operated due to said control gas being added to the

pilot gas; said increased pilot gas flow switching said fluid amplifier divider means to divide said pilot gas flow between the two burners connected to said amplifier means for efficient utilization of said pilot gas.

5. A gas burner control system for the utilization of a plurality of gas flow rates including: gas control means supplied with a combustible gas and having gas outlet means; said gas outlet means normally supplied with at least one gas flow rate; fluid amplifier means having an inlet connected to said gas outlet means; said amplifier inlet manifold to two outlets with each outlet connected to a separate burner; said amplifier inlet further connected to a restricted orifice directed at a side of said inlet; gas flow in said inlet normally flowing in a first of said outlets at low gas flow rates; gas flow in said inlet deflected to flow in both said outlets by a gas jet from said orifice at higher gas flow rates; a first said burner being normally supplied with gas through said amplifier means to maintain a flame; and a second said burner adjacent to said first burner and ignited by said flame; said control means increasing the gas flow to said gas outlet means upon operation of said gas control means; said increased gas flow switching said fluid amplifier means to divide said gas flow between said two burners for efficient utilization of said gas.

6. A gas burner control system for the utilization of a plurality of gas flow rates including: a manifold gas valve supplied with a combustible gas and having a main gas outlet and a pilot gas outlet; said pilot gas outlet normally supplied with at least one gas flow rate; a fluid amplifier having an inlet connected to said pilot gas outlet; said amplifier inlet manifold to two outlets with each outlet connected to a separate burner; said amplifier inlet further connected to a restricted orifice directed at a side of said inlet; gas flow in said inlet normally flowing in a first of said outlets at low gas flow rates; gas flow in said inlet deflected to flow in both said outlets by a gas jet from said orifice at higher gas flow rates; a first said burner being normally supplied with gas through said amplifier to maintain a flame; a second said burner adjacent to said first burner and ignited by said flame; and a main burner connected to said main gas outlet adjacent to said first burner and ignited by said flame whenever said main gas outlet is supplied with gas by said manifold valve; said manifold valve increasing the gas flow to said pilot gas outlet upon operation of said valve; said increased gas flow switching said fluid amplifier to divide said gas flow between said first and second burners for efficient utilization of said gas.
